LIGHTING UNIT

Willis A. Pennow, Cleveland, Ohio, assignor to Westinghouse Electric & Manufacturing Company, East Pittsburgh, Pa., a corporation of Pennsylvania

Application February 25, 1943, Serial No. 477,045

6 Claims. (Cl. 240—41)

My invention relates, generally, to lighting units, and, more particularly, to floodlight projectors and the reflector supporting arrangement thereof.

Heretofore in the manufacture and use of lighting units of which floodlight projectors utilizing incandescent lamps in sizes of 500 and 1000 watts are one example, it has been common practice to use metal reflectors with respect to which there was no particular problem involved in supporting the reflector within the housing due to its durable nature. It has been found, however, that the use of reflectors composed of some frangible material of which glass is a common example, creates the problem of supporting the reflector within the housing in a simple and economical manner, and so that it is not easily damaged from shock but still readily detachable for replacement and servicing. It is to the solution of this problem that the present invention is directed.

Therefore, it is an object of my invention, generally stated, to provide a floodlight projector of the type utilizing a frangible reflector which shall be of simple and rugged construction, economical to manufacture and which shall be so constructed as to effectively protect the reflector against breakage due to shock.

A more specific object of my invention is to provide for mounting a glass reflector in a rigid metal housing in such manner as to minimize the possibility of damage to the reflector due to shock.

A further object of my invention is to provide for supporting a reflector of frangible material within the rigid metallic housing of a lighting unit by means of simple resilient support members associated and positioned within the housing as to effectively support and retain the reflector in the housing in full spaced relation to the inside walls thereof.

Another object of the invention is to provide for utilizing resilient support members for mounting and retaining a glass reflector within the rigid housing of a floodlight projector.

A further object of the invention is to provide for supporting a frangible reflector within the rigid housing of a floodlight projector by means of a plurality of flexible elongated spring members disposed in spaced relation between the reflector and housing.

These and other objects of the invention will become more apparent from the following detailed description when read in conjunction with the drawing, wherein the single figure is a side view in elevation and partly in section of a floodlight

projector embodying the principal features of the invention.

Referring to the drawing, there is shown a lighting unit in the form of a floodlight projector comprising, generally, a rigid metallic housing 10 with a hinged cover 11, including a lens 12 and a lens holding ring 13, and a reflector 14.

The housing 10 is preferably composed of a durable and rigid material, such as metal, is generally bell-shaped and has a necked down end portion in which a socket (not shown) for supporting and conducting current to the lamp 15 is mounted. The front cover 11 of the housing comprises the ring 13 hinged to the housing, as shown at 16, and the lens 12 attached to the ring in any suitable manner. The cover 11 may be clamped to the housing by means of suitable fasteners (not shown).

In this instance, the reflector 14 is composed of a frangible material of which the most common example is glass. In order to provide for supporting the reflector within the housing in such manner that it will not be damaged when subjected to shock and still permit of its ready removal for replacement or cleaning a resilient mounting arrangement is utilized.

In this instance this mounting arrangement comprises a plurality of elongated spring members 17 disposed in spaced relation between the reflector and the inside walls of the housing and so shaped and arranged as to support the reflector in full spaced relation from the housing.

As shown, the resilient support members 17 are preferably composed of flat spring material and are attached to the housing intermediate their ends by the machine screws 18. The point of attachment provides two free ends, the longer, 19, of which is bent upwardly to engage the outside surface of the reflector. The end 21 of this longer portion 19 rests upon the inside of the housing adjacent the rear end of the reflector and thus forms a resilient seat upon which the reflector rests. The shorter portion 22 extends upwardly and beyond the outer rim of the reflector and functions as a front support for the reflector.

In order to provide for retaining the reflector in its proper position within the housing, each of the members 17 is provided with a clip 23 which is attached to the end thereof by means of a machine screw 24. Suitable padding material 25 may be positioned about the outer rim of the reflector between the clip 23 and the shorter end portion 22 of the support member. Padding ma-

terial 26 may be provided on the longer end portions 19 of the support members.

In view of the foregoing, it will be apparent that the plurality of support members 17 function to resiliently support the reflector within the housing as well as to effectively retain it in the proper operating position independently of any additional fastening means. The reflector is supported entirely out of contact with the inside walls of the rigid housing and therefore is protected to a maximum degree from damage due to shock. The use of the detachable fastening or holding clip 23 makes it possible to readily remove the reflector from the housing for replacement or cleaning purposes.

It is to be understood that the supporting arrangement described may be used regardless of the shape of the housing or reflector, it being necessary only to shape and arrange the flexible support members 17 so as to maintain the proper spacing between the reflector and the housing.

While I have shown and described a specific embodiment of my invention, it is to be understood that changes and modifications may be made therein without departing from the principles of the invention.

I claim as my invention:

1. A lighting unit comprising, a rigid and generally bell-shaped housing, a reflector of frangible material mounted within the housing, and a plurality of resilient members in the form of flat spring members disposed in spaced relation about the reflector between said reflector and housing and attached to the housing intermediate their ends only for resiliently supporting the reflector in spaced relation to the inside of the housing, and means carried by the outer ends of said flat spring members for retaining the reflector within the housing.

2. A floodlight unit comprising, a generally bell-shaped rigid housing, a glass reflector mounted therein, a plurality of elongated resilient support members attached to the inner walls of the housing for supporting the reflector therein in spaced relation thereto, said support members being attached to the housing intermediate their ends, and clamp means attached to one end of the support members for engaging the rim of the reflector.

3. A lighting unit comprising, a generally bell-shaped rigid reflector housing, a reflector of frangible material mounted therein, said reflector being of the same general shape as the inside surface of the housing except of smaller diameter throughout its length, a plurality of elongated spring members interposed between the adjacent surfaces of the reflector and housing for resiliently supporting the reflector in spaced relation to the inside walls of the housing, each of said spring members being rigidly secured to the housing intermediate their ends to provide two free end portions one of which is longer than the other, the longer portion being bent upwardly in-

termidate its ends to engage the reflector intermediate its ends and the shorter portion also being bent upwardly to support the reflector at one end thereof, and clip members attached to the end of the shorter portion of the spring members for retaining the reflector against endwise movement.

4. A lighting unit comprising, a generally bell-shaped rigid reflector housing, a reflector of frangible material mounted therein, said reflector being of the same general shape as the inside surface of the housing except of smaller diameter throughout its length, a plurality of elongated spring members interposed between the adjacent surfaces of the reflector and housing for resiliently supporting the reflector in spaced relation to the inside walls of the housing, each of said spring members being rigidly secured to the housing intermediate their ends to provide two free end portions one of which is longer than the other, the longer portion being bowed upwardly intermediate its ends to engage the reflector intermediate its ends and having its free end resting upon the housing and the shorter portion being bent upwardly to support the reflector at the outer end thereof, clip members attached to the end of the shorter portion of the spring members and engaging the outer rim of the reflector for retaining the reflector against endwise movement, and cushioning means interposed between the reflector and spring members at points of engagement.

5. A lighting unit comprising, a generally bell-shaped reflector housing, a reflector of frangible material mounted therein, a plurality of separate elongated resilient support members disposed in spaced relation about the reflector between the outer wall of said reflector and the inner wall of the housing, said support members being attached to the housing intermediate their ends only and having opposed end portions on opposite sides of the point of attachment disposed in spaced relation to the inner wall of the housing and in supporting relation to the reflector to resiliently support the reflector in spaced relation to the housing, and holding means mounted on said support members for retaining the reflector within the housing.

6. A lighting unit comprising, a generally bell-shaped reflector housing, a glass reflector positioned in said housing, and means for resiliently supporting said reflector within the housing in spaced relation to the inner walls thereof including a plurality of elongated flat spring members interposed between the reflector and housing and attached to the housing intermediate their ends only, each of said spring members having one end portion thereof so shaped as to engage the reflector intermediate its ends only and the opposite end portion so shaped as to engage the reflector at the outer rim portion of the reflector only.

WILLIS A. PENNOW.
